SWITCH STRUCTURE

John W. Samzelius, Pittsburgh, Pa., assignor to
Westinghouse Electric & Manufacturing Com-
pany, East Pittsburgh, Pa., a corporation of
Pennsylvania

Application December 23, 1938, Serial No. 247,425

9 Claims. (Cl. 200—168)

My invention relates, generally, to switch structures and more particularly to enclosed switches, commonly known as safety switches, in which it is customary to mount the switches and fuses on an insulating base and to secure the base in a metal box.

For certain kinds of switches it is desirable to utilize a single pole base assembly in which the base is molded of porcelain or other suitable insulating material. One difficulty encountered with a single pole base assembly is the mounting of the base on the sheet metal bottom of the cabinet, since the only space available for the retaining bolts is between the break jaw and the hinge jaw of the switch underneath the switch blade. On the ordinary switch the space between the switch jaws is wide enough for only one bolt, which is not sufficient to keep the base from turning in the cabinet when utilized in the usual manner.

An object of my invention, generally stated, is to provide a switch structure which shall be simple and efficient in operation and which may be readily and economically manufactured and installed.

A more specific object of my invention is to provide for retaining a switch base in position by means of a single mounting bolt.

Another object of my invention is to provide a self-locking and self-aligning mounting bracket for a switch base.

A further object of my invention is to provide for securing the mounting bracket to the switch cabinet.

Still another object of my invention is to provide a resilient mounting for a switch base.

Other objects of my invention will be explained fully hereinafter or will be apparent to those skilled in the art.

In the preferred embodiment of my invention, an insulating switch base is supported by a mounting bracket which is secured to a wall of a switch cabinet. The mounting bracket is so made that the base is securely held in position by a single bolt which is threaded into a bushing that retains the bracket in position and prevents both the base and the bracket from turning in the cabinet. In other embodiments of the invention, the mounting bracket is secured to the cabinet wall by means other than the mounting bolt and its cooperating bushing.

For a fuller understanding of the nature and objects of the invention, reference may be had to the following detailed description, taken in

conjunction with the accompanying drawing, in which:

Figure 1 is a view, partially in section and partially in elevation, of a switch structure embodying my invention;

Fig. 2 is a view, in plan, of a bushing member utilized in the structure shown in Fig. 1;

Fig. 3 is a view, partially in section and partially in elevation, of a modification of the invention shown in Fig. 1; and

Fig. 4 is a similar view of another modification of the invention.

Referring now to the drawing and particularly to Fig. 1, the switch structure shown therein comprises a sheet metal cabinet, only a portion 15 of one wall 10 of which is shown, a switch base 11 composed of porcelain or other suitable insulating material, a switch blade 12 which is hinged to a hinge jaw 13 and engages a break jaw 14 to complete an electrical circuit in the usual manner, terminal members 15 and 16 for making the proper electrical connections to the jaws 13 and 14, respectively, a bracket 17 for supporting the insulating base 11, a bushing 18 for securing the bracket 17 to the cabinet wall 10 and a bolt 19 which is threaded into the bushing 18 to secure the base 11 in the bracket 17.

In order that base 11 may be securely held in position by means of the single retaining bolt 19, the base is provided with a projecting lug 30 having shoulders 21 and 22, as shown. The bracket 17 is made from a sheet metal plate by lancing out and bending up a pair of arms or tongues 23 and 24 which are disposed to engage the shoulders 21 and 22, respectively, of the base 11.

The cabinet wall 10 and the bracket 17 are provided with rectangular openings in which the rectangular bushing 18 is inserted. The bushing 18 may be turned from a rectangular bar to provide a flange 25 on two sides at one end of the bushing, but leaving the body essentially rectangular as shown in Fig. 2. The bushing is made slightly longer than the combined thickness of the cabinet wall 10 and the bracket 17 45 and can, therefore, be locked in place by riveting over or upsetting the top of the bushing. The bolt 19 is threaded into the bushing to secure the base 11 in the clamp 17 between the arms 23 and 24.

It will be seen that when the bolt 19 is tightened, the porcelain base 11 is placed under compression and the arms 23 and 24 are so disposed that they produce a bending moment on the base which opposes the bending moment caused by 55

tightening the bolt 19. Furthermore, the bushing 18 is securely held in position when the bolt 19 is tightened and there is no danger of the bushing coming out of the sub-base or the bracket 17 loosening. By making the holes in the wall 10 and the bracket 17 rectangular and close fitting for the bushing, the bracket 17 and thus the porcelain base 11 will be accurately located without the use of jigs or fixtures when 10 assembling the switch structure.

With this method of assembly, the cabinet and bracket 17 may be painted separately before assembly. There is no spot welding or riveting involved. Therefore, the tapped hole in the 15 bushing 18 will not be clogged up by paint or enamel as is the case with apparatus in which holes are provided in the cabinet for mounting the apparatus in the cabinet, since the holes frequently become clogged with paint, thereby 20 making it necessary to re-tap the mounting holes when the apparatus is assembled in the cabinet.

As explained hereinbefore, the present structure requires only one mounting bolt for securing the switch in position in the cabinet and this 25 bolt may be located substantially at the midpoint of the porcelain between the hinge jaw and the break jaw of the switch where it is made readily accessible by merely opening the plate 12 of the switch. Furthermore, it is possible to so design 30 the clamp or bracket 17 that the bending moments produced in the porcelain will cancel, thereby eliminating all tensile stresses in the porcelain.

Furthermore, breakage of the porcelain base 35 by shock or blows on the cabinet is precluded since the base is so supported by the bracket 17 that it is not in direct contact with the wall 10 of the cabinet.

In the modification of the invention shown in 40 Fig. 3, the insulating base 11 and the switch structure are essentially the same as shown in Fig. 1. The cabinet wall 10 is provided with raised or rib portions 26 on which the bracket 17 rests. The bracket 17 may be secured to the 45 wall 10 by spot welding or riveting the bracket to the raised portions 26 of the wall 10 at points 27, as shown. The bracket 17 is provided with an opening 28 which is threaded to receive the bolt 19, thereby securing the base 11 between the 50 arms 23 and 24 of the bracket 17. The arms 23 and 24 function in the same manner as hereinbefore described to engage the base 11 when the bolt 19 is tightened.

Likewise, the switch 12 and the jaws 13 and 55 14, shown in the modification of the invention illustrated in Fig. 4, are similar to those hereinbefore described. However, in this form of the invention the insulating base 11 is provided with a recess 29 having shoulders 31 and 32 engaged by the oppositely disposed arms 33 and 34 of the bracket 17. In this case, the arms 33 and 34 are formed by merely bending upwardly the end portions of the bracket 17.

The bracket 17 may be welded to the raised 60 portions 26 of the cabinet wall 10 at the points 27, as explained with reference to Fig. 3. The bolt 19 is threaded into the opening 28 provided in the central portion of the bracket 17 which may be re-enforced by a threaded member 35, if 70 desired.

It will be seen that the arms 33 and 34 of the bracket 17 are deflected downwardly to engage the shoulders 31 and 32, respectively, when the bolt 19 is tightened, thereby securely holding the 75 base 11 to the bracket 17. Furthermore, only one

bolt is required to hold the base 11 in position which, as hereinbefore explained, facilitates the manufacture and assembly of switch structures, particularly those in which single pole units are utilized.

From the foregoing description it is apparent that I have provided a simple and economical means of mounting switch structures on supporting walls or in enclosed cabinets which permits the use of either single or multiple pole switch 10 units, as may be desired. Furthermore, the danger of breakage of porcelain switch bases is precluded by the use of the present switch mounting.

Since numerous changes may be made in the 15 above described construction and different embodiments of the invention may be made without departing from the spirit and scope thereof, it is intended that all matter contained in the foregoing description or shown in the accompanying drawing, shall be interpreted as illustrative and not in a limiting sense.

I claim as my invention:

1. In a switch structure, in combination, a 25 supporting wall, an insulating base having projecting shoulders, a bracket for resiliently supporting said base, said bracket having oppositely disposed arms for engaging the shoulders on said base to space the base away from the wall, and means extending through said base into said 30 bracket for securing said base to said bracket at a single point, said bracket being secured to said supporting wall.

2. In a switch structure, in combination, a 35 supporting wall, an insulating base having projecting shoulders, a bracket for resiliently supporting said base, said bracket having oppositely disposed arms for engaging the shoulders on said base to space the base away from the wall, and means extending through said base into said 40 bracket for removably securing said base to said bracket at a single point, said bracket being secured to said supporting wall.

3. In a switch structure, in combination, a 45 supporting wall, an insulating base, a bracket for resiliently supporting said base, said bracket having oppositely disposed upwardly extending arms for engaging said base to maintain the base and the wall in spaced relation, and means disposed in said base between the arms of said bracket for 50 removably securing the base to the bracket, said bracket being secured to said supporting wall.

4. In a switch structure, in combination, a 55 supporting wall, an insulating base, a bracket for resiliently supporting said base, said bracket having oppositely disposed arms for engaging said base to space the base away from the wall, and means disposed in said base substantially midway between the arms of said bracket for 60 removably securing the base to the bracket, said bracket being secured to said supporting wall between said arms.

5. In a switch structure, in combination, a 65 sheet metal support, an insulating base, a sheet metal bracket for resiliently supporting said base, said bracket having oppositely disposed upwardly extending arms for engaging said base to maintain the base and the support in spaced relation, means disposed in said base substantially midway between the arms of said bracket for 70 removably securing the base in the bracket, and means disposed in said support for securing said bracket to said support.

6. In a switch structure, in combination, a 75 sheet metal support, an insulating base, a sheet

metal bracket for supporting said base, said bracket having oppositely disposed upwardly extending arms for engaging said base, means disposed in said support for securing said bracket to said support, and means disposed in said base and engaging the means in said support to secure said base in said bracket.

5 7. In a switch structure, in combination, a sheet metal support, an insulating base, a sheet metal bracket for supporting said base, said bracket having oppositely disposed arms for engaging said base, a bushing disposed in said support for securing said bracket to said support, said bushing having a threaded opening therein, 10 and a bolt removably threaded into said bushing to secure said base in said bracket.

15 8. In a switch structure, in combination, a sheet metal support, an insulating base, a sheet metal bracket for resiliently supporting said base, said bracket having oppositely disposed up-

wardly extending arms for engaging said base to maintain the base and the support in spaced relation, and a single means disposed in said base substantially midway between the arms of said bracket and engaging said bracket to secure the 5 base in the bracket, said bracket being secured to said support.

9. In a switch structure, in combination, a sheet metal support, an insulating base having a recess in the bottom thereof, a sheet metal 10 bracket for resiliently supporting said base, said bracket having oppositely disposed upwardly extending arms for engaging the sides of said recess in the base to maintain the base and the support in spaced relation, and a single means 15 disposed in said base substantially midway between the arms of said bracket and engaging said bracket to secure the base in the bracket, said bracket being secured to said support.
